UNITED STATES PATENT OFFICE

FLOYD C. CAMPBELL, OF MANNING, IOWA

TRACTOR WHEEL ATTACHMENT

Application filed April 17, 1931. Serial No. 530,971.

This invention relates to tractor wheel attachments and aims, among other objects, to provide an improved, quick demountable rim or road band adapted to be applied to a tractor wheel to prevent the traction lugs from damaging road surfaces. The main idea is to provide a relatively simple, sectional road band having improved latches on each section whereby all of the sections may be quickly applied to a wheel without bolts or screws.

Other aims and advantages of the invention will appear in the specification, when considered in connection with the accompanying drawings, wherein:

Fig. 1 is a side elevation, partly in section, showing the preferred form of road band applied to a tractor wheel;

Fig. 2 is a fragmentary sectional view taken on the line 2—2 of Fig. 1; and

Fig. 3 is a sectional view taken on the line 3—3 of Fig. 2.

Referring particularly to the drawings, the preferred form of road band is shown as being applied to a tractor wheel 10 having open, spade lugs 11 on its periphery to provide traction elements. Such lugs are usually arranged in one or more circumferential rows around the rear tractor wheels and are spaced a uniform distance apart. In this instance, the road band is made in sections adapted to be placed on and secured to a row of the lugs, each section being so constructed that it may be fastened on the wheel or removed independently of the other sections.

In Fig. 1, the road band is shown as comprising a plurality of overlapping, channel-shaped sections 12 whose side flanges 13 are adapted to engage the opposite sides of the lugs 11. These sections are preferably made of fabricated sheet metal strips which may be welded or otherwise secured together, the peripheral portions or bands being bent in the form of an arc to engage the ends of a series of lugs on the wheel. This band portion extends beyond one end of the channel flanges 13 to provide an extension 14 to overlap the projecting flanges of an adjacent sections, as shown in Fig. 1. The other end of the band portion on each section terminates short of the beveled end of the side flanges so that,

when the sections are applied, the ends of the band portions will abut each other to form a continuous road contacting surface. However, the projecting ends of the bands may overlap the ends of the bands on the adjacent sections. The side flanges of the sections are shown as being cut away or beveled to permit access to a latch for locking the sections on the wheel.

To prevent the band from slipping on the wheel, each section is shown as having spaced lugs 15 and 16 secured between the side flanges and adapted to straddle one of the spade lugs 11. The lugs 15 are made somewhat longer and stronger than the lugs 16 so as to withstand the traction force when the tractor is driven forwardly or the wheel shown in Fig. 1 is turning in a clockwise direction. It will be understood that two or more pairs of such spaced lugs 15 and 16 may be applied to each band section. The number will depend largely on the length of the sections. Adjacent to one end of each band there is shown a single V-shaped lug 17 adapted to engage the rear face of one of the lugs 11. On the forward face of each of the lugs 17 there is shown a pin 18 adapted to be inserted in an opening or slot in the rear face of the spade lug. The pins thus lock the rear ends of the band sections on the wheel lugs.

In this instance, each section is provided with a removable latch or locking member which includes a bent lever 19 having a pair of L-shaped hooks 20 pivotally connected to it intermediate its ends and adapted to engage one of the spade lugs 11 as shown in Fig. 2. The end of the lever adjacent to the spade lug is shown as having a bent arm or ear 21 to which is connected a coil spring 22 by means of a ring 23. The rear end of the coil spring is removably connected to the side flanges 13 of the band section by means of hooks 24 adapted to be inserted in openings through the flanges. The arrangement is such that, when the lever is swung downwardly as viewed in Fig. 2, or laterally of the wheel, the tension on the spring is released and the lug-engaging hooks 20 may be opened to disengage them from the lug 11.

The bent portion of the lever permits the spring to retain it in locking position because the pivotal axis of the lug hooks lies on one side of the spring. By holding the lever handle at substantially right angles to the road band of the wheel, the hooks 20 may be gripped upon the opposite edges of the open spade lug 11 and the lever swung to its locking position under the band sections to place the spring under tension. Thus, one end of each band section is resiliently locked or connected to the wheel lugs.

In Fig. 1, a series of cleats 25 are shown as being secured to the outer periphery of the band sections so as to afford more traction on hard surfaced roads. These cleats may be made of sheet metal strips and secured to the band sections either by spot welding or by means of bolts, rivets or the like. If desired, they may be removably secured so that they can be replaced when they are worn.

To apply the improved band sections to a pair of tractor wheels, one section of each band may be secured in place and the other sections applied successively on both wheels after the tractor is driven ahead so as to expose successive portions of the wheels. Thus, all of the band sections may be quickly secured to the wheels without using a jack and without any wrenches or other special tools. In fact, a driver can apply the bands in a few minutes.

From the foregoing description, it will be seen that the band sections can easily be manufactured of sheet metal. The length of the sections is such that they can be stacked together or nested so as to occupy a small storage space. The improved locking devices can be removed from each section and can be applied very easily and quickly when the sections are attached to a wheel. Moreover, such bands do not interfere with ordinary scrapers for keeping the traction wheels clean and can be used without removing the scrapers. Furthermore, the band sections can be applied to spade lugs of either the hollow or solid type, it being only necessary to make slight alterations in solid lugs to provide for engagement of the locking hooks or members.

Obviously, the invention is not restricted to the illustrative embodiment thereof except as defined in the appended claims.

What is claimed is:

1. A road band for tractor wheels having a circumferential series of lugs comprising, in combination, a plurality of substantially channel-shaped sections adapted to be slipped over the lugs; means on each section interlocking with a lug; and a lever-operated locking member detachably connected to each section at one end and removably secured to one of the lugs.

2. A road band for tractor wheels hav-

ing a circumferential series of lugs comprising, in combination, a plurality of substantially channel-shaped sections adapted to be slipped over the lugs and each having an extension overlapping the other; means on one end of each section interlocking with a lug; and a locking device including a lever and hook members removably secured to the other end of each section and adapted to be connected to one of the lugs.

3. A road band for tractor wheels having a circumferential row of spade lugs comprising, in combination, a plurality of channel-shaped sections presenting flanges adapted to straddle the lugs; means at one end of each section positively interlocking with one of the lugs; and a lever-operated latch device connected to the other end of each section having means removably to secure said other end to another one of said lugs.

4. A road band for tractor wheels having a circumferential row of spaced lugs comprising, in combination, a plurality of channel-shaped sections having flanges adapted to straddle the lugs; spaced lugs in the channel-shaped sections adapted to straddle one of the lugs on the tractor wheel so as to prevent the sections from slipping on the wheel; a pin secured to one end of each section adapted to interlock with one of the wheel lugs; a coil spring removably secured to the other end of each section; and a lever-operated latch member carried by said coil spring having hooks to engage another wheel lug whereby each section of the band can be applied independently of the others and all of the sections may be applied in succession.

In testimony that I claim the foregoing as my own, I have hereto affixed my signature.

FLOYD C. CAMPBELL.
